UNITED STATES PATENT OFFICE

ABRAHAM LEVINE, OF ELIZABETH, NEW JERSEY, ASSIGNOR TO PRESTO LOCK CORPORATION, OF NEW YORK, N. Y., A CORPORATION OF NEW YORK

DESIGN FOR A BRIEF-CASE LOCK

Application filed March 17, 1930. Serial No. 34,911. Term of patent 7 years.

To all whom it may concern:

Be it known that I, ABRAHAM LEVINE, a citizen of the United States, residing at Elizabeth, Union County, and State of New Jersey, have invented a new, original, and ornamental Design for a Brief-Case Lock, of which the following is a specification, reference being had to the accompanying drawing, forming part thereof.

I claim as my invention:

The ornamental design for a brief-case lock substantially as shown.

ABRAHAM LEVINE.
